210,563

CONTAINER INSERT FOR A COSMETIC PACKAGE

Georges Kocens, 235 Camino Descanso,
Palm Springs, Calif. 92262

Filed Apr. 6, 1967, Ser. No. 6,553

Term of patent 14 years

(Cl. D86—10)

The back is conventionally plain.

I claim:

The ornamental design for a container insert for a cosmetic package, substantially as shown and described.
